(57) **CLAIM**

The ornamental design for an insulating beverage container with cup as shown and described.

DESCRIPTION

FIG. 1 is a right side perspective view of my new design for an insulating beverage container with cup;

FIG. 2 is a right side view thereof;

FIG. 3 is a left side view thereof;

FIG. 4 is a front view thereof;

FIG. 5 is a rear view thereof;

FIG. 6 is a bottom perspective of FIG. 1;

FIG. 7 is an exploded view of FIG. 1;

FIG. 8 is a top view thereof; and,

FIG. 9 is bottom view thereof.

All broken lines in the drawings are for illustrative purposes only and form no part of the claimed design.

1 Claim, 8 Drawing Sheets
